[57] CLAIM

The ornamental design for a transparent storage envelope for a flexible magnetic computer disc, substantially as shown and described.

DESCRIPTION

FIG. 1 is a front elevational view of a transparent storage envelope for a flexible magnetic computer disc embodying my new design;

FIG. 2 is a rear elevational view thereof;

FIG. 3 is an enlarged scale right end elevational view of FIG. 1;

FIG. 4 is an enlarged scale left end elevational view of FIG. 1;

FIG. 5 is a top plan view thereof;

FIG. 6 is a bottom plan view thereof;

FIG. 7 is a perspective view thereof showing the top and the side panel portion of the envelope in open condition;

FIG. 8 is a perspective view showing the envelope in bent condition; and

FIG. 9 is an enlarged scale cross-sectional view taken along line 9—9 of FIG. 1.

FIG. 1**FIG. 2****FIG. 3 FIG. 4****FIG. 5****FIG. 6****FIG. 7****FIG. 9****FIG. 8**
